UNITED STATES PATENT OFFICE.

BENJAMIN C. SMITH, OF BROOKLYN, ASSIGNOR TO FRED ADEE & CO., OF NEW YORK, N. Y.

STOP-COCK BOX.

SPECIFICATION forming part of Letters Patent No. 311,265, dated January 27, 1885.

Application filed March 3, 1884. (No model.)

To all whom it may concern:

Be it known that I, BENJAMIN C. SMITH, of Brooklyn, in the county of Kings and State of New York, have invented an Improvement in 5 Stop-Cock Boxes, of which the following is a specification.

Stop-cock boxes have been made of cast-iron in the form of a tube through which the key or rod of the stop-cock passes, and at the bottom there is a space for the reception of the stop-cock. These stop-cocks are usually placed in the pipe leading from the street-main to the house or building, and are employed for cutting off the water-supply. The 15 boxes are buried in the earth, and the upper end is usually level with the sidewalk.

Boxes constructed as aforesaid do not protect the stop-cock from the earth, which is liable to fill in the sides of the box where it is 20 forked for the passage of the water-pipe. Besides this the stops that limit the movement of the plug of the cock are sometimes designedly misplaced, so that the cock is open when it appears to be closed.

25 My invention is made for removing the aforesaid objections; and it consists in movable side plates for closing the fork at the lower end of the box, and in a check that is confined by a guide-ring in the upper part of the box, so that the stops are always in the correct position in relation to the stop-cock.

In the drawings, Figure 1 is a vertical section of the box and elevation of the stop-cock. Fig. 2 is a detached side view of the lower 35 end of the box. Fig. 3 is a section in larger size of the upper end of the box. Fig. 4 is a plan of the same. Fig. 5 is a side and plan view of the guide-ring, and Fig. 6 is a side and plan view of the check.

40 The water or gas pipe *a* is provided with a stop-cock, *b*, and *c* is the rod or key that extends up to the surface of the ground. These parts are of usual character. Usually the rod *c* will be of square iron, with its lower end firmly 45 secured into a socket in the upper part of the plug.

The box is composed of the cast-iron tube *d*, with forks *e* at the lower end, that straddle the pipe *a*, and there are feet *f*, that extend 50 out horizontally and serve to keep the box in

place and prevent the frost lifting the same. The side plates, *h*, are made with openings that are of a size to fit the pipe *a*, and such plates are passed upon the pipe—one at each side of the cock—before the pipes and cock are 55 connected up. After the forks have been placed over the pipe and cock the plates *h* are brought up at each side of the forks and the box raised or the pipe depressed, so that the plates slip in behind the lugs *l*, and the 60 parts are firmly connected together and the sides of the fork closed so as to exclude the earth, which is to be filled in around the box, as usual. Near the upper end of the tubular box and within the same there are two inwardly-projecting lugs that form stops *r* to the projection *s* upon the check-piece *o* through a square hole in which the key or rod *c* passes. This check is made with a flange or head that rests upon the top of the guide-ring *u*, the 70 projection *s* being below the said ring, and there is a notch at 2 in this guide-ring which allows the projection *s* to be passed through the same. The guide-ring *u* rests upon the stops *r*, and in order to hold the guide-ring in 75 place I make a projection, *v*, at one side to enter a recess in the interior surface of the tubular box and insert a screw or screws, *n*, that pass through the tubular box into the edge of the guide-ring. The parts are made 80 so that the slot in the guide-ring *u* is above one of the stops *r*; hence the check *o* cannot be taken out after the parts are placed together, and it is necessary to pass the projection *v* of 85 the check through the guide-ring before the ring is put into the top of the box, and this has to be done before the box is applied to the key *c*, because such ring has to be entered at an inclination to insert the projection *v* into its recess. In consequence of this construction it is impossible to tamper with or 90 change the check *o* without breaking some of the parts or taking up the box.

I claim as my invention—

1. The combination, with the stop-cock and 95 tubular box having a fork and feet at the lower end, of the side plates, *h*, surrounding the tube *a*, or the tubular portion of the cock, and acting to close the sides of the fork, substantially as set forth.

2. The combination, with the movable plates *h*, stop-cock, and pipe, of the tubular metal box having the forks and feet at the lower end, and the projections *l*, behind which the plates are received, substantially as set forth.

3. The combination, with the tubular stop-cock box, the stop-cock, and its rod or key *c*, of the check having a projection, the guide-ring that receives the check, the stops be-

neath the guide-ring for limiting the movement of the check, and the fastenings for the guide-ring, substantially as set forth.

Signed by me this 28th day of February, A. D. 1884.

BENJ. C. SMITH.
